ADJUSTABLE INLET STRUCTURE FOR CONDUITS

Ethan Frank Murray, Columbus, Ga., assignor to
Lummus Cotton Gin Company, Columbus, Ga.,
a corporation of Georgia

Application June 8, 1933, Serial No. 674,920

3 Claims. (Cl. 302—34)

My invention relates generally to improvements in adjustable conduits and the like, but has especial reference to the so called telescopes, or intake terminals, of pneumatic conveyors such as are used for supplying cotton gins, gin feeders, etc.

In order to efficiently gather cotton into the pneumatic conveyor from a wagon or pile, it has been the practice to make up the metal intake conveyor pipe section of telescoping members, and by means of a canvas or leather joint, to connect such intake section, or telescope, as it is known in the art, to the adjacent conveyor pipe section. Such construction enables the telescope to be manually swung around in different directions to gather up the cotton and its length increased or reduced as occasion may require. However, while a canvas or leather sleeve joint connection between the telescope and the conveyor proper, gives the telescope ample freedom of movement, yet such joints quickly wear out or become punctured and must be frequently renewed.

It is therefore the primary object of the present invention to eliminate the necessity of using said objectionable canvas or leather joints, and to provide a novel and improved airtight conduit providing connection between the telescope and conveyor, which connection may and preferably will be of metal, so as to provide an all-metal telescope and conveyor construction having all the advantages of the leather or canvas joint without the objections thereto.

A further object of the invention is to provide a conveyor and telescope construction wherein the connection between a telescope and conveyor provides a support for both.

The invention also resides in a novel hand grip for the telescoping members of the telescope, and in certain novel features of construction, combination and arrangement of parts to be hereinafter described and claimed, reference being had to the accompanying drawings which illustrate a now-preferred embodiment.

In the drawings, wherein the same reference characters designate the same parts in all views,

Figure 1 is a side elevational view of a portion of a pneumatic cotton conveyor incorporating my novel telescope;

Figure 2 is an end elevational view of the same;

Figure 3 is an enlarged vertical sectional view through one side of members 18, 19 at pivot 22;

Figure 4 is an enlarged vertical detail view de-

picting the channel 13, a part of elbow 10 and associated elements in vertical section;

Figure 5 is a section on line 5—5 of Figure 2; and

Figure 6 is a detail side elevational view of the handle and clamp structure.

Referring to the drawings by reference characters, numeral 7 denotes the pneumatic conveyor pipe leading to the gins or cotton gin feeders. This pipe 7 is shown as having its outer end telescopically receiving the cylindrical nipple end 8a of what is shown in Fig. 1 as a rectangular pipe section 8.

The pipe section 8 is secured as at 9 to an elbow 10. At the back of the elbow 10 is fastened the bearing bracket 11 whose horizontal bearing portion carries the stub shaft 11a which is fixedly secured therein by set screws 11b as shown.

Suitably secured to rafters or other appropriate supports 12 is a channel iron 13 having riveted against the outer sides at one end a bearing bracket 15, while similarly secured to the sides of said angle iron or channel 13 adjacent the opposite end thereof is the bracket 14. The bracket 15 is U-shaped in cross-section and the ends of its legs provide attachment to the channel iron 13. The back of the bracket 15 provides a bearing 15a (see Fig. 4) for receiving the outer end of the stub shaft 11a. A set collar 16 on the end of shaft 11a tends to maintain the bearing portion 15a of bracket 11 against the bearing 15a of bracket 15.

The other channel iron carried bracket 14 provides the annulus 14a which constitutes a support for the nipple end 8a of the pipe section 8 previously mentioned.

From the foregoing it will be understood that the elbow 10 is adapted to swing about a horizontal axis provided by the bearing brackets 14, 15, and which axis is concentric with the axis of conveyor pipe 7. As will be apparent as the description proceeds, the horizontal pivot structure just recited provides one element of a dirigible mounting or universal connection between the pneumatic conveyor pipe 7 and the telescope or inlet connection of which pipe 8 and elbow 10 are a part.

Furthermore, it will be evident from the structure recited that the channel iron 13 with the depending brackets 14, 15 not only provides a support for the telescope but also provides a support for the inlet end of the conveyor 7, proper.

From an inspection of Figures 1 and 2, it will be apparent that the elbow 10 has its lower end 55

secured as at 17 to the outlet end of a two-part casing comprising the interfitting swingably connected sections 18, 19. Fig. 1 illustrates the sides of the interfitting casing sections 18, 19 as curved correspondingly and that the section 18 extends into the section 19. The pivot studs 22 connecting the sections 18, 19 are disposed centrally of the casing with their axes at right angles to the axis of the stub shaft 11a which cooperates with brackets 15, 14 for supporting the elbow for movement about a horizontal axis. Of course, the pivot studs 22 which connect the sections 18, 19 of the casing are likewise disposed in a horizontal plane and this pivot working with the elbow pivot, 15 and at right angles thereto, will obviously provide a universal coupling or joint that will enable the suspended telescope to be moved about in all directions for gathering up cotton from a pile in a wagon or upon the surface of the ground.

As has been mentioned in connection with Fig. 1, the sides of the casing sections 18, 19 are curved so as to permit relative swinging of same about the axis 22. However, Fig. 2 illustrates the ends of the interfitting casing sections 18, 19 as being plane. The sections provide a relatively loose fit at their ends and sides and in consequence of this loose fit, I provide a sealing means for preventing the entry of air into the casing 18, 19 from outside of the same. This sealing means, as shown, is provided by the laterally extending upper flange 19a which is coextensive with the rim of section 19, and carries the U-shaped clip 20 which carries the flexible flashing or sealing element 21. This element 21 bears against the adjacent surface of section 18 so as to effectually seal the joint between sections 18, 19. Suitable fasteners such as 20a are available for securing the U-shaped clip element to flange 19, and also for securing the flashing element in place within the clip element.

Adverting to the pivot studs 22 connecting the sections of casing 18, 19 it will be observed from an inspection of Fig. 3 that the outer end walls of section 19 carry bearing portions 23, while the opposite inner surfaces of section 18 carry the reinforcement plates 24. Thus, an effective bearing is provided by the bearing portions 23 and the ferrules 25 which are seated in the end walls of section 18, and in the reinforcing plates 24 thereof, so as to bear against the inner faces of bearing portions 23 and be held thereagainst by tightening up the nuts 22a on the bolts or studs 22.

The casing section 19 has a rounded nipple extension 19b which is connected as at 28 to the upper member 29 of the telescope. It is to be observed that the telescope member 29 extends slidably into the telescope member 30.

The telescope member 30 has secured to same a novel adjustable handle structure which comprises spaced clamps 31 which comprehend a pair of substantially semicircular sections 31a, 31b having opposed parallel terminals 31c which are adapted to be drawn toward one another by means of bolts 33, so that the clamp members 31 will be snugly engaged with pipe 30. The bolts 33 are disposed inwardly of the outer ends of the lateral terminals 31c.

Companion lateral terminal portions 31c have bolts 35 adjacent their outer ends adapted to extend through vertical hand grip bars 36 for securing the same at their ends to the spaced clamps 31. The handle structure described has the advantage of permitting ready vertical adjustment of same along telescope section 30, as occasion may require. The handles 36 will be permanently secured to the clamps 31 as clamp sections 31a, 31b will be comparatively springy, 10 and tightening up of the bolts 33 enables gripping action to take place without disturbing the handle securing means.

Figure 2 illustrates the telescope section 30 as having a lateral ear 38 receiving a cable 39 which extends upwardly about a pulley 40 carried by a rafter or support 12. The depending end of cable 39 carries the counter weight 41 for balancing the weight of the lower telescope section 30. Thus, the conveyor sections 29, 38 will remain in any relative adjusted relationship.

The practical advantages of the described embodiment of the invention will be readily understood and appreciated by those skilled in the art. It will be obvious that many changes and modifications may be made in the structure herein shown and described without departing from the spirit and scope of the subject matter claimed hereinafter.

Having thus described my invention what I claim as new is:

1. In a pneumatic conveyor telescope, an overhead support, a hanger depending therefrom, a conveyor pipe having one end disposed in said hanger, an elbow in swivelled connection at one end with said hanger supported end of the conveyor pipe, an inlet conduit depending from the other end of said elbow and supported thereby, a bracket on the outer curve of said elbow, a cooperating bracket depending from said overhead support in proximity to the elbow bracket, and a pivot pin received in both of said brackets in axial alignment with said conveyor pipe.

2. In a pneumatic conveyor telescope, an overhead support, a conveyor pipe suspended therefrom, an elbow in swiveled connection with said conveyor pipe at one end, an inlet conduit, a swing joint connecting said inlet conduit and the other end of said elbow, and means pivotally suspending said elbow from said overhead support in axial alignment with said conveyor pipe.

3. In a pneumatic conveyor telescope, an overhead support, a conveyor pipe, an elbow in swiveled connection at one end with said conveyor pipe, a hanger on said support and providing a common support means for the associated ends of said elbow and conveyor pipe, an inlet conduit, a swing joint connecting said inlet conduit and the other end of said elbow, a bracket depending from said overhead support substantially in vertical alignment with said inlet conduit, and means pivotally connecting said bracket and the elbow.
